UNITED STATES PATENT OFFICE.

ERNEST GREENE, OF NEW YORK, N. Y.

DESIGN FOR A DISPLAY-STAND.

SPECIFICATION forming part of Design No. 25,196, dated February 25, 1896.

Application filed January 4, 1896. Serial No. 574,389. Term of patent 7 years.

To all whom it may concern:

Be it known that I, ERNEST GREENE, of New York city, in the county and State of New York, have invented and produced a new and original Design for Display-Stands, of which the following is a full, clear, and exact description.

Reference is to be had to the accompanying drawings, forming a part of this specification, in which similar characters of reference indicate corresponding parts in all the views.

Figure 1 is an elevation of a display-stand embodying my new design, parts being broken away and others in section. Fig. 2 is a detail sectional plan view of the finial on line 2 2 of

Fig. 1, and Fig. 3 is a sectional plan view on the line 5 5 of Fig. 1.

The leading feature of my design consists of the display-stand comprising the polygonal body composed of superposed series of panels defined by ornamental framework, the dome of ornamental metal-work, and the ornamental finial.

I claim—

The design for a display-stand herein shown and described.

ERNEST GREENE.
